REPLACEABLE LIP DREDGE BUCKET

John Crouch, Natoma, Calif.

Application January 17, 1942, Serial No. 427,153

9 Claims. (Cl. 37—141)

My invention relates to dredge buckets, and particularly to an improved form of replaceable bucket lip.

In certain locations the moving of earth in quantity is accomplished most economically by the use of an endless chain of digging buckets. Typical of such uses is the digging out of stream beds and banks in mining operations. Another example is the deepening of a channel for navigation in a river. Other uses will immediately occur to those skilled in the art.

The lips which cut into the earth wear through abrasive action, and become distorted or broken through contact with rocks or boulders. This wearing away of the lips reduces the capacity of the individual buckets, and hence the output of the entire bucket chain, by as much as 50% of the initial volume.

A number of types of replaceable cutting lips have been suggested. They are advantageous as compared with the replacement of the entire bucket in being much less expensive, and in enabling the dredge operator to keep his production more nearly constant in both volume and cost.

Their use is attended by many problems, however, which have not been satisfactorily solved in the known types. It is the purpose of this disclosure to set out the construction of an improved form of bucket in which these difficulties are overcome.

The use of renewable lips requires, first, that the lips be adequately anchored to the bucket; and next, that they be removed and replaced quickly, so that the entire dredge need only be idle for a minimum period of time. The lips must be strong enough to resist distortion and breakage, and the bucket should be designed so that strains exerted on the lips will not deform it.

The usual digging buckets are roughly elliptical in cross-section as viewed from above, with the longer elliptical axis parallel to the pivotal connections to the other buckets constituting the continuous chain, which is mounted on a digging ladder attached by suspension lines to and carried by a boom. Cutting action occurs along the forward edge of the buckets when the boom is moved straight ahead and also along the side portions when the boom is swung from side to side. The latter method is common in dredging gold bearing gravel. The boom is mounted on a barge which is floated over the area to be worked, temporarily anchored, and the boom and bucket chain swung from one side of the stream to the other, making successive arcuate cuts. The cut-

ting action in such case will be effected by the leading portions of the lip.

When operating in this fashion, the "live loads," or force exerted by the motors driving the continuous chain of buckets, is exerted through the bucket lips, and is usually distributed between two or three of them which are in simultaneous contact with the earth. In hard ground, the strain on the individual lips may be substantially increased. The buckets tend to "ride up" over hard ground or bedrock instead of digging through as they would in less resistant formations.

As the level of the digging ladder is thus raised, its weight will be supported partly or wholly on the few bucket lips in contact with the rock instead of on the suspension lines. Exemplary of the additional strain thus effective, in one typical installation the "live load," or digging resistance, was 120,000 pounds, while the "dead load," or digging ladder weight transferred from the suspension lines to the lips in contact with the earth was 500,000 pounds. Obviously, the cutting edges and the means for attaching the lips to the buckets must be designed to resist both the "live" and "dead" loads.

The forces acting may be analysed in relation to the individual bucket and lip by considering them to be resolved into components parallel and normal to the lip cross-section shown in Fig. 1. Use will be made of the reference characters applied specifically in the detailed description hereafter, when necessary to an understanding of the force analysis. The components due to the reaction of the ground against the cutting edge and parallel to the lip section tends to upset the lip about the forward edge of the upper rim 7 of the hood as a fulcrum. This tendency I overcome by properly positioning the stop lugs inside the hood adjacent the tangs of the lip. If the lip were to be rotated about the forward upper hood edge as a fulcrum, the arcuate path of the terminal lip portions would pass directly through these inner stop lugs, and so a direct resistance in compression is offered to such movement.

When the bucket line is being propelled in a reverse direction, as in withdrawing it from a cut, the frictional resistance is effective as a force component parallel to the lip section of Fig. 1 and tending to unseat the lip by arcuate movement about the upper edge of the rim shoulders 10 as fulcrums. The lip of my invention prevents this result by being shaped so that the arcuate path through which the forward edge of the lower lip portion 27 would extend directly

through the hood seat 11 and the lip movement would be prevented thereby.

Certain prior art lips have tried to resist the upsetting forces by interlocking the lip ends with the hood. Such interlocking structures require complicated movements of the lip relative to the hood, or pre-stressing and deforming of the lip, for assembly. My invention permits straight line movement of the lip into position in the hood, and requires no deformation of the lip, while still securely maintaining the lip against such forces as tend to unseat it. No special assembly equipment is required in the field.

The weight of the digging ladder may be represented by components largely effective normally to the lip section of Fig. 1, tending to force the lip rearwardly in the bucket. In the prior art the engaging surfaces terminally of the lips have been set at angles which were not normal to the line of action of these force components. The result has been that the ends of the lips tended to work on the inclined planes thus provided, out of proper alinement with the hood. I overcome this by making the terminal engaging surfaces substantially normal to the line of action of these forces. This position is also substantially normal to a tangent to the hood and lip outer surfaces adjacent their planes of engagement.

The combination of all these strains tends to distort the lip so that it loses its intimate engagement with the hood. This action is progressive, and shortly renders the lips unserviceable. Not only do the lips become split and twisted, but the rim of the hood may be twisted and the rivet holes torn or stretched so that extensive repairs to the hood proper may be required. I have found that the construction of my preferred form of lip is very effective in resisting such deterioration.

These advantages are obtained, in brief, by providing a tapered seat into which the lip is easily placed or removed. The construction enables an even more secure fit when cutting pressure is applied by so proportioning the parts that upsetting forces are overcome within the structure, by making the lip and hood engaging surfaces substantially normal to the forces transmitted therebetween, and by so shaping the lip and seat that they may be fitted together by a simple, straightline movement without pre-stressing or distorting.

The construction which I have designed will be more fully understood by reference to the drawings and description following, and to the objects of my invention, which include: providing an improved form of replaceable bucket lip; providing a bucket lip in which stresses exerted against the cutting edge are effective to unite the lip more firmly to the bucket; affording a bucket and lip joint in which the tendency to work out of alinement is eliminated; neutralizing forces tending to upset a bucket lip; providing a bucket lip which can be set in place with a minimum of manipulation; providing a lip in a form which can be replaced when worn out more simply than can those known in the prior art; and eliminating the necessity for distorting or prestressing the lip to join it to the hood.

These and other objects will be apparent to those skilled in the art from a study of the disclosure following. It is to be understood that the invention is intended to include any modifications necessary to adapt it to fulfill these aims,

and all such changes in form and structure as may be made with ordinary skill by those familiar with the field. All such variations I intend to comprehend within the scope of the appended claims.

5 In the drawings:

Fig. 1 is a side sectional view of a bucket and lip incorporating my invention;

Fig. 2 is a top view of the sectional bucket and lip showing of Fig. 1;

10 Fig. 3 is a fragmentary view in section showing the joint between one of the extremities of the bucket lip and the bucket, taken as indicated by line 3-3 of Figs. 1 and 2; and

15 Fig. 4 is a fragmentary section taken along line 4-4 of Figs. 1 and 2.

In Fig. 1, I have shown my invention as applied to a typical bucket 1 forming a part of an endless bucket chain, not shown in the drawing. Bucket 1 includes leading bosses 2 and trailing bosses 4, formed integrally with a body 3 or hood 5 in which the earth is carried. Hood 5 is roughly elliptical in cross-section, expanding in smooth curves from its bottom 6 to its upper rim 7. Upper rim 7 extends around about two thirds of the outwardly flared forward side 9 of hood 5. An engaging face 8 is formed on rim 7, and rim shoulders 10 extend normally upward from rim 7 at either side of hood 5 near its rear. It will be understood that these relative terms will be used in connection with the drawing as follows: that portion adjoining the connections to the bucket chain will be called the rear, and the cutting sides of the bucket the front; the leading portion of the bucket will be referred to as the top, and the trailing portion as the bottom.

The inner surface of bucket hood 5 is finished, as by grinding adjacent the rim 7, to form a tapering seat 11 for the reception of an engaging face 12 formed along the lower portion of removable lip 14. The engaging face 12 tapers cooperatively with the seat, so that a snug nesting fit is obtained. Rearwardly on each side of hood 5, integrally formed stop lugs 15 project inwardly therefrom. An engaging face 16 is formed on lug 15 substantially coplanar with the rim shoulder 10, but extending downwardly from the hood rim 7.

50 The lip 14 is formed in substantial continuation of the curvature of hood 5, with the cutting edge 17 sharpened and the lip body 18 thickened for strength. An outer seat 13 is formed on lip 14, engaging face 8 on rim 7. The lip terminates at each end in an inwardly flared portion 19 of which a part is cut away, leaving a tang 20 offset inwardly by the thickness of hood 5 to form outer lip shoulder 21. The offset 21 engages rim shoulder 10, transmitting stresses applied through the lip normal to the lip section of Fig. 1 directly to the hood 5. Immediately beneath the tang 20, which is in intimate contact with the inner surface of the hood 5, that part of the inwardly flared lip portion 19 which was cut away forms an engaging surface, or inner lip shoulder 24, butting against the engaging surface 16 of stop lug 15. Terminal rivets 25 secure tangs 20 to hood 5, while additional intermediate rivets 26 extending through hood 5 immediately below rim 7, and through the lower portion 27 of lip 14, join the hood and lip together as an operative unit. I prefer that the rivets 25 and 26 be countersunk flush with the inner surface of the lip, allowing the rivet heads 29 to project 75 beyond the outer surface of the bucket. Ob-

viously, however, any other suitable arrangement could be used, as rivet heads projecting both inwardly and outwardly, bolts instead of rivets, or equivalent means.

Going back to the construction of the rim shoulder 10 and the stop lug 15: the engaging face 16 is substantially parallel with the shoulder 10, and both are arranged so that the lip 14 may be put on and off by a simple straight line movement. The entire lip is held so that its ground engaging face 12 is parallel to the ground seat 11 on the hood, and is kept in such alined position while it is being inserted.

The rim shoulder 10 and engaging face 16 are substantially normal to the hood rim 7, as are the engaging faces 16 of stop lug 15 and 24 of the inwardly offset rim portion 19. The planes in which they lie are held parallel to the line along which the lip is moved into position, referred to in the claims as the line of generation, so that as the lip nests in the hood, the engaging surfaces near the tangs 20 meet smoothly, without requiring the lip to be twisted about or carefully manipulated.

The engaging surfaces 10 and 21 and 16 and 24 are also normal to a tangent to the surface of the hood and lip at the line of engagement or generation. This means that stresses transmitted between the lip and hood at these points will not tend to cause relative movement between the two, as is the case where these engaging surfaces are other than normal to the stress line. In prior art buckets these faces are commonly inclined, so that lip tends to ride up out of position, or to spread or pinch in, depending on the general design.

It will be apparent also on close inspection of the showing of Fig. 1, which is to scale, that the lip 14 cannot be upset about the upper rim 7 of the hood 5, as the engaging face 16 of lug 15 is directly in the arcuate path 31 which inner lip shoulder 24 would have to traverse.

Similarly, the upsetting of lip 14 about a fulcrum formed by the upper edges of rim shoulder 10 and outer lip shoulder 21 is prevented by the presence of tapering seat 11 directly in the arcuate path 32 in which the engaging surface 12 of the lip would have to move.

In summary, my invention provides for a lip which can be easily replaced without the use of unusual tools, and without pre-stressing, while at the same time being fundamentally more stable and tending to maintain the initial tight relationship for a longer period of time. The invention thus contributes to economy in operation, since the lips require renewing less frequently, and can be replaced much more rapidly when necessary.

What I claim is:

1. A dredge bucket, comprising a body member, means formed on said body member for pivotally linking said bucket into a bucket chain, a hood formed on said body member, a rim formed on said hood, an engaging face formed on said rim, a tapered seat formed within said rim, rim shoulders formed terminally of said seat and substantially normal to the adjacent surface of said hood, lugs extending into said hood substantially co-planar with said shoulders, and a removable lip formed in substantial continuation of the curvature of said hood including a tapered portion arranged to nest with said tapered hood seat, an outer seat formed on said lip to engage with said engaging face formed on said rim, in-

wardly offset portions formed terminally of said lip, inner shoulders formed on said offset portions arranged to engage said lugs, and outer shoulders arranged to engage said rim shoulders.

5 2. A dredge bucket, comprising a body member, means for connecting said body member in a bucket chain, a hood formed on said body member, a rim formed on said hood, rim shoulders terminating said rim, an inner stop lug formed on said hood adjacent each of said shoulders, a tapered seat formed within said rim, an engaging face formed on said rim, parallel seating faces formed on said stop lugs and rim shoulders, a removable lip formed in substantial continuation of the curvature of said hood, a tapered lower face formed about said lip and arranged to mate with said tapered seat, an outer seat formed on said lip to engage with said engaging face formed on said rim, terminal portions inwardly offset from said lip, an outer shoulder formed by said offset portions and arranged to mate with said rim shoulder, an inner shoulder formed on each of said offset portions and arranged to mate with one of said stop lug seating faces, a tang formed on each of said inwardly offset portions arranged to nest within said hood, and means for securing said lip to said hood.

15 3. A dredge bucket, comprising a body member, means for connecting said body member in a bucket chain, a hood formed on said body member, a rim formed on said hood, rim shoulders terminating said rim, an engaging face formed on said rim, an inner stop lug formed on said hood adjacent each of said shoulders, a tapered seat formed within said rim, parallel seating faces formed on said stop lugs and rim shoulders, a removable lip formed in substantial continuation of the curvature of said hood, a tapered lower face formed about said lip and arranged to mate with said tapered seat, an outer seat formed on said lip to engage with said engaging face formed on said rim, terminal portions inwardly offset from said lip, an outer shoulder formed by said offset portions and arranged to mate with said rim shoulder, an inner shoulder formed on each of said offset portions and arranged to mate with one of said stop lug seating faces, a tang formed on each of said inwardly offset portions arranged to nest within said hood, and means for securing said lip to said hood.

25 4. In a dredge bucket, the combination of a body member, means for linking said body member to a chain of said buckets, a hood formed on said body member, a rim defined on said hood, an engaging face formed on said rim, rim shoulders terminating said rim, a tapered seat formed within said rim, stop lugs formed inwardly of said hood, a removable lip, a tapered portion formed on said lip and arranged to mate with said tapered rim seat, an outer seat formed on

30 said lip to engage with said engaging face formed on said rim, portions inwardly offset from said lip on each side of said hood, an outer rim engaging surface formed by each of said offsets and arranged to seat against one of said rim shoulders, a tang formed by each of said offsets arranged to nest snugly within said hood, an inner engaging face formed on each of said offsets and arranged to engage one of said stop lugs, and means to fix said lip to said hood; said outer seat and said outer rim engaging surface,

35 5. In a dredge bucket, the combination of a body member, means for linking said body member to a chain of said buckets, a hood formed on said body member, a rim defined on said hood, an engaging face formed on said rim, rim shoulders terminating said rim, a tapered seat formed within said rim, stop lugs formed inwardly of said hood, a removable lip, a tapered portion formed on said lip and arranged to mate with said tapered rim seat, an outer seat formed on

40 said lip to engage with said engaging face formed on said rim, portions inwardly offset from said lip on each side of said hood, an outer rim engaging surface formed by each of said offsets and arranged to seat against one of said rim shoulders, a tang formed by each of said offsets arranged to nest snugly within said hood, an inner engaging face formed on each of said offsets and arranged to engage one of said stop lugs, and means to fix said lip to said hood; said outer seat and said outer rim engaging surface,

45 6. In a dredge bucket, the combination of a body member, means for linking said body member to a chain of said buckets, a hood formed on said body member, a rim defined on said hood, an engaging face formed on said rim, rim shoulders terminating said rim, a tapered seat formed within said rim, stop lugs formed inwardly of said hood, a removable lip, a tapered portion formed on said lip and arranged to mate with said tapered rim seat, an outer seat formed on

50 said lip to engage with said engaging face formed on said rim, portions inwardly offset from said lip on each side of said hood, an outer rim engaging surface formed by each of said offsets and arranged to seat against one of said rim shoulders, a tang formed by each of said offsets arranged to nest snugly within said hood, an inner engaging face formed on each of said offsets and arranged to engage one of said stop lugs, and means to fix said lip to said hood; said outer seat and said outer rim engaging surface,

55 7. In a dredge bucket, the combination of a body member, means for linking said body member to a chain of said buckets, a hood formed on said body member, a rim defined on said hood, an engaging face formed on said rim, rim shoulders terminating said rim, a tapered seat formed within said rim, stop lugs formed inwardly of said hood, a removable lip, a tapered portion formed on said lip and arranged to mate with said tapered rim seat, an outer seat formed on

60 said lip to engage with said engaging face formed on said rim, portions inwardly offset from said lip on each side of said hood, an outer rim engaging surface formed by each of said offsets and arranged to seat against one of said rim shoulders, a tang formed by each of said offsets arranged to nest snugly within said hood, an inner engaging face formed on each of said offsets and arranged to engage one of said stop lugs, and means to fix said lip to said hood; said outer seat and said outer rim engaging surface,

65 8. In a dredge bucket, the combination of a body member, means for linking said body member to a chain of said buckets, a hood formed on said body member, a rim defined on said hood, an engaging face formed on said rim, rim shoulders terminating said rim, a tapered seat formed within said rim, stop lugs formed inwardly of said hood, a removable lip, a tapered portion formed on said lip and arranged to mate with said tapered rim seat, an outer seat formed on

70 said lip to engage with said engaging face formed on said rim, portions inwardly offset from said lip on each side of said hood, an outer rim engaging surface formed by each of said offsets and arranged to seat against one of said rim shoulders, a tang formed by each of said offsets arranged to nest snugly within said hood, an inner engaging face formed on each of said offsets and arranged to engage one of said stop lugs, and means to fix said lip to said hood; said outer seat and said outer rim engaging surface,

75 9. In a dredge bucket, the combination of a body member, means for linking said body member to a chain of said buckets, a hood formed on said body member, a rim defined on said hood, an engaging face formed on said rim, rim shoulders terminating said rim, a tapered seat formed within said rim, stop lugs formed inwardly of said hood, a removable lip, a tapered portion formed on said lip and arranged to mate with said tapered rim seat, an outer seat formed on

and said rim shoulders, and said inner engaging faces and said stop lugs, respectively, being arranged in such position as to oppose adequately stresses encountered between said lip and said hood.

5. In a dredge bucket, the combination of a body member, means for linking said body member to a chain of said buckets, a hood formed on said body member, a rim defined on said hood, rim shoulders terminating said rim, a tapered seat formed within said rim, an engaging face formed on said rim, stop lugs formed inwardly of said hood, a removable lip, a tapered portion formed on said lip and arranged to mate with said tapered rim seat, an outer seat formed on said lip to engage with said engaging face formed on said rim, portions inwardly offset from said lip on each side of said hood, an outer rim engaging surface formed by each of said offsets and arranged to seat against one of said rim shoulders, a tang formed by each of said offsets arranged to nest snugly within said hood, an inner engaging face formed on each of said offsets and arranged to engage one of said stop lugs, and means to fix said lip to said hood; said outer seat and said outer rim engaging surface, and said rim shoulders, and said inner engaging faces and said stop lugs, respectively, being arranged in such position as to oppose adequately stresses encountered between said lip and said hood, and said hood and lip being arranged to resist by direct compressive engagement forces tending to upset said lip from its seated position.

6. In a dredge bucket having a hood and a removable lip, means for relating said lip to said hood, comprising male and female surfaces formed peripherally about said lip and within said hood; a rim face on said hood, and an outer seat on said lip, for respective engagement; inner and outer engaging surfaces terminally formed on said lip, and stop lugs and rim shoulders formed on said hood for respective engagement arranged to permit straight line entry of said lip into said hood and to present normal faces so as to oppose adequately digging stresses encountered.

7. In a dredge bucket having a hood and a removable lip, means for relating said lip to said hood, comprising male and female surfaces formed peripherally about said lip and within said hood; a rim face on said hood, and an outer seat on said lip, for respective engagement; inner and outer engaging surfaces terminally formed on said lip, and stop lugs and rim shoulders formed on said hood for respective engagement arranged to permit straight line entry of said lip into said hood and to present normal faces so as to oppose adequately digging stresses encountered, and means for securing said lip to said hood.

8. A dredge bucket, comprising a body member, means for connecting said body member in a bucket chain, a hood formed on said body mem-

ber, a rim formed on said hood, an engaging face formed on said rim, rim shoulders terminating said rim, an inner stop lug formed on said hood adjacent each of said shoulders, a tapered seat formed within said rim, parallel seating faces formed on said stop lugs and rim shoulders, a removable lip formed in substantial continuation of the curvature of said hood, a tapered lower face formed about said lip and arranged to mate with said tapered seat, an outer seat formed on said lip to engage with said engaging face formed on said rim, terminal portions inwardly offset from said lip, an outer shoulder formed by said offset portions and arranged to mate with said rim shoulder, said lip being arranged so that an arc centered at the upper edge of said outer shoulder and passing through the lower edge of said tapered lower lip face centrally of said lip will extend directly through said tapered rim seat, an inner shoulder formed on each of said offset portions and arranged to mate with one of said stop lug seating faces, a tang formed on each of said inwardly offset portions arranged to nest within said hood, and means for securing said lip to said hood, said inner and outer lip shoulders being disposed so as to oppose adequately stresses encountered.

9. A dredge bucket, comprising a body member, means for connecting said body member in a bucket chain, a hood formed on said body member, a rim formed on said hood, an engaging face formed on said rim, rim shoulders terminating said rim, an inner stop lug formed on said hood adjacent each of said shoulders, a tapered seat formed within said rim, parallel seating faces formed on said stop lugs and rim shoulders, a removable lip formed in substantial continuation of the curvature of said hood, a tapered lower face formed about said lip and arranged to mate with said tapered seat, an outer seat formed on said lip to engage with said engaging face formed on said rim, terminal portions inwardly offset from said lip, an outer shoulder formed by said offset portions and arranged to mate with said rim shoulder, said lip being arranged so that an arc centered at the upper edge of said outer shoulder and passing through the lower edge of said tapered lower lip face centrally of said lip will extend directly through said tapered rim seat, an inner shoulder formed on each of said offset portions and arranged to mate with one of said stop lug seating faces, said inner lip shoulder being so positioned that an arc drawn through the lower edge thereof from the central portion of said hood upper rim as a center will extend directly through said inner hood stop lugs, a tang formed on each of said inwardly offset portions arranged to nest within said hood, and means for securing said lip to said hood, said outer seat and said inner and outer lip shoulders being disposed so as to oppose adequately stresses encountered.

JOHN CROUCH.
